Olivier Lafrenière

UNITED STATES PATENT OFFICE.

OLIVIER LAFRENIERE, OF NEW YORK, N. Y.

HORSE-COLLAR.

Specification of Letters Patent No. 22,562, dated January 11, 1859.

To all whom it may concern:

Be it known that I, OLIVIER LAFRENIERE, of the city, county, and State of New York, have invented a new and useful Improvement 5 in Horse-Collars; and I do hereby declare that the following is a full, clear, and exact description of the same, reference being had to the annexed drawings, making a part of this specification, in which—
10 Figure 1, is a longitudinal central section of my invention. Fig. 2, is a front or face view of ditto.
Similar letters of reference indicate corresponding parts in the two figures.
15 This invention consists of an improved article of manufacture, viz, a horse-collar having its lower part provided with a metallic tube to give form to and hold the packing and otherwise made as herein set forth.
20 To enable those skilled in the art to fully understand and construct my invention I will proceed to describe it.

A, represents a horse collar constructed according to my invention. The upper part 25 of the collar is constructed of the usual form and of the usual materials. The extreme lower part however of the collar is different from those of usual construction as will be readily seen by referring to Fig. 30 2. Instead of having the lower part of the sides *a*, *a*, extend around in semi-circular form or with a gradual curve as indicated by the dotted lines in Fig. 2, the lower part 35 of the collar has a jog or loop *B*, which extends down farther than the usual curve, but allows the sides *a*, *a*, to be of the ordinary form.

Within the jog or loop *B*, a hollow metal tube *C*, is placed. This tube is bent or 40 curved corresponding with the desired form of the jog or loop and is of such diameter as to correspond to the front rim or projection *b*, in front of the hames *c*, and when covered to form a continuation of said rim 45 or projection *b*, which is constructed in the usual way it being merely stuffed with straw. The jog or loop *B*, with the exception of the tube *C*, is constructed precisely the same as the other parts of the collar. The hames *c*, 50 are applied to the collar in the usual way and are of usual construction they being

merely bent or formed to correspond to the form of the jog or loop *B*, as shown clearly in Fig. 2.

By this invention the bearing of the lower 55 part of the collar will extend below the point pressed upon by the collars of present construction and the pressure of the collar will be too low to inconvenience the horse. The plan of extending the lower part of the 60 collar farther down than usual has been previously essayed but was found impracticable on account of the liability of the sides *a*, *a*, to spring or give under the draft. In order to obviate this difficulty the metal 65 tube *C*, is employed and fitted in the collar as shown and described. The tube *C*, combines lightness with strength and effectually prevents the springing or distending of the sides *a*, *a*, the collar by its use being rendered 70 equally as stiff or inflexible as those of ordinary construction.

It will be understood that the ends of the straw stuffing are inserted within the tube *C*, which thus forms a holder for the base 75 of the stuffing, of a firm and durable character, besides greatly cheapening the construction of the collar. In the construction of the ordinary collar, it is a matter that requires skill and consumes time, so to form 80 the straw packing as that it shall present the proper form and have a compact, rounded and gradually tapering start. If it is not properly formed, or is loosely done, the collar soon gives way at this point, and becomes 85 useless.

It is entirely new, so far as I know, to employ a tube at the base of the collar, which tube serves as a holder, from the interior of which the straw rises. 90

Having thus described my invention, I claim and desire to secure by Letters Patent, as an improved article of manufacture—

A horse-collar, having its lower part provided with a metallic tube *C*, to give form 95 to and hold the packing, and otherwise made as herein set forth.

OLIVIER LAFRENIERE.
